Filed Sept. 5, 1974, Ser. No. 503,621

Term of patent 14 years

Int. Cl. D12—16

U.S. Cl. D12—156

FIG. 1

FIG. 2

FIG. 3

FIG. 1 is a top plan view of a cover for a pickup truck bed showing my new design;

FIG. 2 is a side elevational view thereof; and

FIG. 3 is a side elevational view of a cover for a pickup truck bed showing a second embodiment of my new design, the sole difference being in the arrangement and configuration of the side window and railing.

The front and rear of the cover are open and the edges of the side panels are of a conventional thickness.

The broken lines in the drawing are for illustrative purposes only.

The side opposite to that shown in FIGS. 2 and 3 is a mirror image of the sides shown in the respective views.

I claim:

The ornamental design for a cover for a pickup truck bed as shown and described..
